CLAIM

The ornamental design for a food jar, as shown and described.

DESCRIPTION

FIG. 1 is a front perspective view of a food jar in accordance with my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a front perspective view thereof with the food jar cap of the food jar lid open.

The broken lines shown in FIGS. 1–8 depict portions of the food jar which form no part of the claimed design. The innermost center surface and the adjacent ring-shaped surface, shown in FIG. 7, form no part of the claimed design. None of the broken lines form part of the claimed design.
